United States Patent Office

Des. 178,417
Patented July 31, 1956

178,417

CAN PUNCH

Joseph C. Mullner, St. Paul, Minn.

Application August 26, 1953, Serial No. 26,589

Term of patent 14 years

(Cl. D44—29)

I claim:

The ornamental design for a can punch, as shown.
